Philco Radio and Television Corporation, Phil-
adelphia, Pa., a corporation of Delaware

Application March 29, 1945, Serial No. 118,777

Term of patent 7 years

(CL. D67—3)

To all whom it may concern:

Be it known that I, Donald E. Dailey, a citizen
of the United States, residing in Bryn Mawr,
Montgomery County, Pennsylvania, have in-
vented a new, original, and ornamental Design
for a Refrigerator Cabinet, of which the follow-
ing is a specification, reference being had to the

accompanying drawing forming part thereof, in
which Figure 1 is a perspective view of a refrig-
erator cabinet, showing my new design.

I claim:

The ornamental design for a refrigerator cab-
inet, as shown and described.

DONALD E. DAILEY.
